SOUND REPRODUCER

Edwin H. Smythe, Evanston, Ill., assignor, by
mesne assignments, to Western Electric Com-
pany, Incorporated, New York, N. Y., a corpo-
ration of New York

Original application August 17, 1926, Serial No.
129,731. Divided and this application January
4, 1929. Serial No. 330,172

18 Claims. (Cl. 181—31)

This invention relates to sound reproducers adapted to act directly on the air and to impart vibrations to the air from relatively large surfaces.

This is a division of my application, Serial No. 5 129,731, filed August 17, 1926, issued as Patent 1,895,494 on January 31, 1933.

An object of the invention is to reproduce efficiently and faithfully all sounds within the audible range.

10 A related object of the invention is to distribute sound vibrations uniformly over one or more sound radiating surfaces.

Another object of the invention is to transmit sound waves in phase from a plurality of direct 15 acting sound radiating surfaces.

In one of its embodiments the invention provides one or more large radiating surfaces driven substantially edgewise with respect to the general plane of the surfaces, the compressional and exten- 20 sional stresses in the material produced by the driving force being converted into movements of the surface transverse to its plane, these movements setting up sound waves in the surrounding air. Such a structure is relatively rigid in the direction of drive and yielding in a direction trans- 25 verse thereto.

The invention in another of its embodiments provides a sound radiator in the form of a hollow structure having side walls of light elastic mate- 30 rial which are driven toward and away from each other in response to a driving force common thereto. The driving force is applied to the radiator in such a way that the sound vibrations involve relatively large areas and are distributed 35 substantially uniformly over the side walls. In a particular embodiment of the invention the radiator comprises a tubular member having two side walls which are supported at a point intermediate the ends of the walls and are driven in unison at 40 an end of the walls in a direction substantially edgewise or perpendicular to the plane of the support.

In a modified form of the invention each side wall of the radiator is composed of two flat trans- 45 versely rigid sections joined together to form an extended surface and driven at the point of junction of the two sections. Each side wall may be made transversely rigid by ribs or corrugations, the driving force being applied at the middle of 50 the wall, while the opposite ends of the wall are so mounted as to be constrained against trans- verse movement.

In one embodiment of the invention the side 55 walls of the radiator are bulged in opposite direc- tions so that the movement of the driven edge

toward and away from the support in response to the vibration of the driving member produces a transverse movement of the walls in opposite directions. The walls of the radiator may be alike in area, mass and rigidity, and when actuated by 60 the common driving unit are caused to transmit waves that for the low frequencies are in substantially the same phase over the exterior surfaces and are in the opposite phase over the interior surfaces of the radiator, the resulting air 65 waves of opposite phase being separated from each other by the walls of the radiator to avoid neutralization of their effects. This construction tends to increase the effective sound radiation 70 of the device.

In constructing the radiator in accordance with the invention there are a number of factors which may be varied to produce any desired action with respect to frequency response. The walls of the radiator may be made of various materials, of 75 various dimensions, and of various curved and angular relations between the parts, and the weight and stiffness of the walls may be varied to give the radiator the required mass and elasticity constants for transmitting, converting into re- 80 quired relative movements, and distributing the driving force. A simple and efficient driving member, preferably in the form of a long, light and rigid tube, as disclosed and described in the parent application heretofore referred to, may 85 also be provided for applying the driving force uniformly along the extended edge or intermediate portion of the radiator.

The various features of the invention will be 90 described in connection with the accompanying drawing in which like reference characters designate similar parts in the several figures, and in which:

Fig. 1 is a perspective view of a sound radiator 95 having curved walls with a support intermediate the ends of the walls;

Fig. 2 is a perspective view of a sound radiator having side walls formed of two rigid flat sections;

Figs. 3, 3A, and 4 illustrate three modifications 100 of the sound radiator shown in Fig. 2 including modified driving and supporting means. In Fig. 3A the driving means is shown connected to the diaphragm slightly off center in order to clarify the showing.

The sound radiator shown in Fig. 1 comprises 105 a long, hollow structure having two enclosing side walls 5 and 6 of light, elastic material, such for example as stiff paper, fastened together along their upper longitudinal edges preferably by 110

means of a rigid binding strip or a rib 7 of light material such as duralumin.

The diaphragm comprising the walls 5 and 6 may be mounted on a base 9 between a pair of tubular uprights 10 and may have a driving element connected to the member 16 as shown and described in the aforementioned parent application.

The support for the diaphragm 5, 6 comprises a bowed bridging member 73 mounted on an angular supporting bar 74 which extends longitudinally through the diaphragm, the bar 74 being in turn mounted on the base 9. Opposite upturned edges 75 of the bridging member 73 are fastened, for example, by means of cement to the inner surfaces of the diaphragm walls 5 and 6.

The motor element 12 for actuating the walls 5 and 6 is carried by support 13 mounted on vertical rods 14, which are supported in the tubular uprights 10 secured to the base 9. The rods 14 may be locked in any desired vertical position by means of suitable screws 15. The motor element 12 may be of the type disclosed and claimed in U. S. Patent 1,709,571, issued April 16, 1929 to H. C. Harrison. The driving rod of the motor element is connected to the longitudinal rib 7 of the radiator by means of the clamping member 16 mounted midway between the ends of the radiator. Since walls 5 and 6 of the radiator are curved outwardly from each other a downward movement of the driven edge 7 will drive the walls of the radiator away from each other and increase the volume of the space enclosed between them. With a pair of walls 5 and 6 having similar mass and elasticity constants, the device when actuated by low frequency vibrations will act upon the air as a pulsator sending out from the two outer walls air pressure waves of corresponding phase and amplitude, the corresponding waves of opposite phase produced by the inner surfaces of the walls being prevented from direct intermingling with the waves from the outer surfaces by the interposition of the material of the elongated walls of the radiator.

The degree of curvature of the radiating surfaces 5 and 6 may be varied by adjusting the angle at the joining of the edges of the two walls. Generally, the slighter the normal curvature of these surfaces with respect to the direction of application of the driving force, the greater will be the volume change in the enclosed space between the two surfaces for a given movement of the driving element. As the curvature of the surfaces approaches the semi-circular, the volume change becomes less, and beyond this point the volume change for the same direction and amplitude of movement at the driving point is in the opposite direction. Furthermore, the less the curvature the greater is the rigidity of the structure in the direction of drive, and correspondingly the greater is the length of wave in the material and the greater is the area involved. Accordingly, the normal curvature of the walls 5 and 6 should be less than semi-circular and preferably 65 of relatively slight curvature. The walls 5 and 6 should also be secured at their driven edge in such a way that the curvature of all points between these edges is in the same direction, as illustrated. This is necessary since any double curvature or 70 buckling of the walls would tend to produce transverse movement of the same surface in opposite directions and thus reduce the amount of radius of the transmitted waves.

One advantage secured by the above structure 75 is that which arises from the air transformer

effect at low frequencies between the inner surface of the double-walled diaphragm and the openings at the ends thereof. Under proper conditions, the relation of the inner surface area to the area of the openings at the ends of the hollow structure will be such as to add air mass reactance to the diaphragm throughout the lower frequency range, and thus permit a relatively stiff diaphragm structure to be employed without loss of the low frequency tones. The transformer 80 ratio may be changed as desired by changing the length or shape of the hollow structure, or both, in order to obtain the required ratio between the area of the active inner surfaces and the area of the opening of the enclosed space into the outer air. Another advantage of this structure lies in the baffle-plate action of the structure in that the portions of the walls more remote from the driving point function as separating walls between the areas of compression and rarefaction 90 on the outer and inner surfaces of the diaphragm.

If desired, the bridging member 73 may be made of a sheet of light, stiff material similar to that of the walls of the diaphragm, in which case the transverse component of the movement due to 100 the driving force will cause sound radiation directly from the surfaces of the bridging member, while the longitudinal component of movement that moves the walls 5 and 6 in opposite phase to produce a pulsator action will cause sound radiation from the surfaces of these walls. The bridging member 73, however, in this particular embodiment, need not be a radiator of sound energy, but may serve merely to cooperate with the driving edge in causing the transverse movement of 110 the balanced walls of the diaphragm. In the performance of this function it may be replaced by open arms or toggle lever connections between the supporting bar 74 and the side walls. By attaching the supporting member along the middle 115 of the side walls, the lower half of the tubular member is left free to execute movements symmetrically with those of the upper half in response to the vibrations applied to the upper driving edge.

Fig. 2 illustrates a modification of the invention on which the side walls of the diaphragm instead of being curved, are each composed of two flat, transversely rigid sections. The side walls 76 and 77 may each be constructed in two substantially rectangular sections, and each section may comprise two sheets of material such as light, stiff paper. One of the sheets of material of each section of a wall is preferably ridged or corrugated at intervals, the corrugations being more or less closely spaced, while the other sheet of material is flat and is pasted or cemented to the corrugated sheet. The portions of the corrugated sheet lying between adjoining corrugations are in a flat plane, thus producing a composite wall 135 with one flat surface and one corrugated surface with the corrugations spaced at any desired interval, and the wall being light and having a very satisfactory degree of transverse rigidity. The borders of the flat sheet of each wall section 140 may project beyond the borders of the corrugated sheet at each edge, the adjoining edges of the flat sheets being fastened together in any suitable manner, as by means of cement, to provide hinged connections 78 between adjoining transversely rigid sections. The lower edges of the walls 76 and 77 are fastened together in any suitable manner, and may be supported in a slotted base 79. The upper edges of the diaphragm walls are fastened together by means of a longitudinal 150

rib 80 which is adapted to be driven in a direction perpendicular to the plane of the support 79 in a manner similar to that described in connection with Fig. 1, or the junction edge may be driven by the power distributing tube or torsional line drive element as described and shown in the parent application.

Fig. 3 illustrates a composite system of sound radiating surfaces embodying elements of a number of the forms of the invention hereinbefore described. In this construction the walls of the system are preferably of the form illustrated in Fig. 2, made transversely rigid by ridges or corrugations. The side walls 76 and 77 are made up of four rectangular transversely rigid sections secured together at their adjoining edges. Bridging diametrically opposite junction points or edges of side walls 76 and 77 is a sound radiating surface consisting of transversely rigid sections 82 joined together and driven at an intermediate point 87 by the motor element 86. This motor element is mounted upon the supporting bar 83, which bar extends lengthwise of the structure and carries an extension 84 through the medium of which the whole radiating system of the diaphragm is supported, the lower junction line of the two side walls 76 and 77 being fastened to the extension 84 along the line 85. All of the members of this diaphragm system cooperate in the production and radiation of sound. The movement which is imparted to the transverse radiating surface 82 by the motor element 86 causes the transverse portion 82 to act as a sound radiator, and also to impart transverse movement to the side walls 76 and 77, this movement also resulting in the radiation of sound waves from the side walls. It may be seen that the sound radiator of Fig. 3 represents the combination of a number of simpler elements which have a capacity of operating independently of other elements of the combination as sound radiators. For instance, the upper halves of the side walls 76 and 77 may be removed from the combination, and the part which is left, consisting of the lower half of each of the side walls joined to the outer edges of the transverse radiating member 82 constitute an operative radiating system. This modification, to a slightly reduced scale, is shown in Fig. 3A. In this simpler form, the vibrations applied along the central line of the transverse member 82 cause it to radiate sound directly, and also to produce a component of motion transverse to the direction of drive that causes the movement of the lower side wall members and the radiating of sound from them. Or if the lower side wall portions 76' and 77' in the simplified component of the structure of Fig. 3 just considered, are deprived of their sound radiating capacity and retain merely their capacity for affording supports for the outer edges of a transverse radiating member 82 which constrain the outer edges at 81 against transverse movement or movement in the direction of the driving force, the transversely radiating member 82 is then the sole radiator of sound in the system. The system of Fig. 3, therefore, may be seen to consist of a number of simple elements capable of acting independently as sound radiators, or capable of combination in the form illustrated to combine their sound radiating effect. The driving force may be applied at the middle of the transverse member 82, if desired, by means of the elongated power distributing tube disclosed in the parent application heretofore mentioned.

The sound radiator as shown in Fig. 4 is generally similar to the structure shown in Fig. 1

with respect to the point of application of the driving force and the means for supporting the moving system, and resembles the structure shown in Fig. 3 in the matter of the nature of the radiating surfaces employed. In Fig. 4, the corrugated bridging member 82 is supported at its center by means of a bar 89 similar to the bar 74 in Fig. 1, and the motor element 86 which serves to actuate the diaphragm at the junction point of the upper joined edge of the walls is mounted on a similar bar 90. In this construction, the constraint in the direction of the driving force and the freedom transverse to the direction of the driving force afforded by the bridging member 82 cause the lower sections of the diaphragm walls to execute a movement for low frequencies symmetrical with the movements of the upper sections of the walls. The transverse component of movement of the side walls is accentuated by disposing the elements 82 of the bridging member at a more acute angle with respect to each other.

Various structural modifications may be made in the sound radiator as described above without departing from the scope and spirit of the invention. In all of the modifications illustrated, for example, the hollow diaphragms may be so mounted that the line of support and the line of drive are vertical instead of horizontal. In some cases where very large diaphragms are employed, a vertical support and a vertical drive may have the advantage of preventing any biasing of the driving armature that might result from the weight of the diaphragm parts that are to be moved.

What is claimed is:

1. A sound reproducer comprising a hollow structure with yielding walls, a bridging member within said structure connecting said walls and hinged thereto, and means for producing relative movement in response to sound vibrations between said bridging member and said walls.
2. A sound reproducer comprising a hollow open-ended structure having a pair of yielding walls bowed in opposite directions, a bridging member within said structure hinged to said walls at the mid portions thereof, and means for driving said member in response to sound vibrations.
3. A sound reproducer comprising a partial enclosure with yielding walls, a bridging partition within said enclosure joined to said walls, said bridging partition being normally bowed, and means for producing relative movement between a point on said partition and the walls of said enclosure in a direction to change the shape of said partition, said movement being in accordance with vibrations representing sound.
4. A sound reproducer comprising a support, a hollow, open-ended direct-acting sound radiating surface hinged at an edge to said support, and means for driving said surface at a point remote from said hinged edge.
5. A sound reproducer comprising a hollow structure with yielding walls, a support, a bridging member mounted on said support and hinged to said walls, and means for driving said walls in response to sound vibrations.
6. A sound reproducer comprising a hollow structure having a pair of walls one of which is corrugated, a bowed bridging member within said structure and hinged to the walls thereof, and means for driving said walls relatively toward and away from each other in response to sound vibrations.
7. A sound reproducer comprising a pair of

double-wall diaphragms joined together edge to edge, means for supporting said diaphragms, and means for driving said diaphragms at their junction.

8. A sound reproducer comprising a hollow structure having a plurality of oppositely disposed spaced sound radiating surfaces, a bridging member within said structure having its edges adjacent those of said sound radiating surfaces, a support for said surfaces, and driving means mounted on said support and attached to said bridging member intermediate its ends, whereby actuation of said bridging member in accordance with sounds to be reproduced causes relative movement

10 of said surfaces and said member thereby producing acoustic pulsations in the volume bounded by said surfaces and member.

9. A direct-acting diaphragm for electro-acoustic apparatus, having a plurality of elements each rigid in itself, the edges of said elements being straight, two edges of each element being adjacent two edges of the other elements, and a flexible connection forming a straight-line hinge between the adjacent edges of such rigid elements, 25 said elements forming a partial enclosure.

10. A direct-acting diaphragm for electro-acoustic apparatus, having a plurality of substantially rectangular elements, said elements constituting the walls of a partial enclosure and 30 a bridging member within the enclosure connecting the walls, and a flexible connection forming a straight-line hinge between straight adjacent edges of said rectangular elements.

11. A direct-acting diaphragm for electro-acoustic apparatus having a plurality of elements of substantially rectangular form, a flexible connection between straight adjacent edges of said rectangular elements, and means for connecting other adjacent edges of said elements flexibly to 35 stationary supports.

12. A direct-acting diaphragm for electro-acoustic apparatus, having a plurality of substantially rectangular elements arranged with

edges adjacent to form a tubular enclosure and a central hinge connecting adjacent edges of said elements, two of the adjacent edges being connected to a stationary support.

13. A direct-acting diaphragm for electro-acoustic apparatus, having a plurality of substantially rectangular elements, a central hinge connecting the adjacent edges of said elements, and means for connecting two adjacent edges of said elements to a stationary support. 80

14. A diaphragm for electro-acoustic apparatus, having a plurality of elements located side by side, a hinge connecting adjacent edges of said elements, and a metallic member embracing said hinge and clamped firmly thereon. 85

15. A sound reproducer comprising a hollow structure with yielding bowed walls, a bridging member within said structure joined to said walls so as to have a straight line hinge connection therewith, and means for imparting acoustic vibrations to said structure. 90

16. A sound reproducer comprising a tubular, hollow, open-ended structure with yielding oppositely bowed walls, a bridging member within said structure connecting said walls and joined thereto to form straight line hinges therewith, and means for producing relative movement between said walls and bridging member. 100

17. A sound reproducer comprising a hollow structure with yielding bowed walls, a bridging member having a central hinge portion and having hinge connection with said walls, and means for causing relative movement of said walls and member in response to sound wave impulses. 105

18. A sound reproducer comprising a hollow structure with yielding walls, a bridging member having a central hinge portion and having hinge connection with said walls, and means connected to the central hinge portion for causing relative movement of said walls and member in response to sound wave impulses. 110
